UNITED STATES PATENT OFFICE.

HERMAN A. FEIGELMAN, OF PATERSON, NEW JERSEY.

FOLDING BOX.

Application filed November 10, 1924. Serial No. 748,800.

This invention relates to display devices, and its principal object is to provide a device of this character in which articles in the nature of men's garters, or other articles of a generally flat form, may be displayed, the same being inexpensive and simple in construction and adapted to have the article readily assembled therewith and held thereby in a secure and attractive manner. 10 A further object is to provide a display holder and means associated therewith whereby to form a box or container for the article wherein it may be packed and shipped, practically enclosed, and thereupon displayed for sale. In the best form of the invention, the container, including the holder and said means, is formed from a single piece of sheet material, as in the example shown in the accompanying drawing and 15 hereinafter described.

In said drawing,

Fig. 1 is a plan view of a container embodying the invention, its closure being open;

25 Fig. 2 is a sectional view on the line 2—2, Fig. 1;

Fig. 3 is a sectional view on the line 3—3, Fig. 1;

30 Fig. 4 is a plan of the blank; and

Fig. 5 is a side elevation showing the position of the parts in the act of forming the container from the blank.

The blank shown in Fig. 4 is a piece of 35 suitably stiff sheet material, as pasteboard. It is rectangular and elongated and includes three main rectangular wall-forming portions *a*, *b* and *c* of substantially equal dimensions, wall *a* being adapted in the completed container to form its bottom, wall *b* 40 its top and wall *c* a false bottom. Alternating with the portions forming these walls are portions *d*, *e* and *f* each rectangular and as long as each of said portions *a*, *b* and *c* is wide transversely of the blank but appreciably narrower. When the blank is folded 45 on the transverse dotted lines shown between *a*—*d*, *d*—*b*, *b*—*e*, *e*—*c* and *c*—*f* (so that *a*, *b* and *c* become the bottom wall, top wall and false bottom of the container) walls *d* 50 and *e* will form two opposite walls of the container and wall *f* will stand inside and more or less upright as shown in Fig. 3, engaging at its free edge at the juncture between walls *d* and *b'* for a purpose to be explained. The other two side walls of the 55 container may be afforded by lateral exten-

sions *a'* of the wall *a*, to be bent up at right angles to wall *a* on the dotted lines shown, and these extensions may have flaps *a''* to be bent up at right angles to the extensions 60 on the dotted lines shown; when these walls *a'* and their flaps *a''* are properly positioned in forming the container the flaps extend in under the top wall *b* as shown by dotted line in Fig. 1. Thus the box is closed at all 65 four sides and also the necessary stability is afforded by the walls *a'*. The box or container may be closed at the corners and added stability afforded by the tabs *d''* and *e''*, these tabs being bent on the dotted lines 70 shown and tucked inside of the walls *a'*. There may be also an ear *g* extending from the free side of the wall *a* and adapted to enter a slit *h* on the line of fold between *c* and *e*. 75

To form the holder for the articles I slit the blank in the portion forming the false bottom *c* on two lines *i* extending transversely of the blank. This will leave a strap *j* between the two lines. I also slit the material on pairs of spaced lines *k* extending from opposite sides of the strap. This will leave the strap joined to the remainder of the blank or piece by connections *l*, a pair on each side of the strap. These connections 80 may be bent on lines extending lengthwise of the strap (as on the dotted lines shown) so that the part including the strap and connections will be arched as shown in Fig. 3, leaving the strap elevated out of the plane 85 of the wall *c*. The article to be displayed may be then inserted under the strap, resting on the remainder of wall *c* as a background, when the various parts of the blank have been brought into the relation whereby 90 95 to form a box or container as already described. The article is protected from exposure at the back by wall *a*. Usually the article will be assembled with the blank before it is manipulated to form the box 100 or container.

The container being designed especially as a display container I form the top wall *b* with an opening *b'* and this may be produced so as to provide a closure therefor 105 by slitting wall *b* on three lines at right angles to each other, thereby leaving the part of the material bounded by the slits and indicated by *b''* as such closure, the same being capable of hinging on the dotted line 110 shown.

The wall *f* not only engages the walls *b'*

and *d* at their juncture but is inclined or divides the angle formed by these two walls so that it is thus locked against tilting in either direction, or maintained in a definite 5 position, and holds the false bottom in face to face contact with the bottom *a*.

Having thus fully described my invention, what I claim and desire to secure by Letters Patent is:

- 10 1. A display container formed of one piece of stiff sheet material and including an apertured top wall, opposite side walls depending from the top wall, a bottom and a false bottom extending from the respective side walls and the latter lying for substantially its full extent on and in face to face contact with the former, and a wall extending from that edge of the false bottom which is remote from the side wall to which 15 said false bottom is connected into contact with and dividing the angle between said top and the other wall at their juncture and
- 20

thereby holding said false bottom in such contact with the bottom.

2. A display container formed of one 25 piece of stiff sheet material and including an apertured top wall, opposite side walls depending from the top wall, a bottom and a false bottom extending from the respective side walls and the latter having an 30 elevated strap-forming intermediate portion and the portions thereof flanking said intermediate portion each lying for substantially its full extent in face to face contact with said bottom, and a wall extending from that edge of the false bottom which is remote from the side wall to which said false bottom is connected into contact with and dividing the angle between said top and the other side wall at their juncture and thereby 35 holding said flanking portions of the false bottom in such contact with the bottom.

In testimony whereof I affix my signature.
HERMAN A. FEIGELMAN.
